JOHN YANCY SATTERWHITE, OF WAGONER, OKLAHOMA.

SPLICE-JOINT FOR CAR-SILLS.

1,094,682.

Specification of Letters Patent. Patented Apr. 28, 1914.

Application filed February 21, 1913. Serial No. 750,018.

To all whom it may concern:

Be it known that I, JOHN YANCY SATTERWHITE, a citizen of the United States of America, residing at Wagoner, in the county of Wagoner and State of Oklahoma, have invented a new and useful Improvement in Splice-Joints for Car-Sills, of which the following is a specification.

The invention relates to improvements in 10 splice joints for car sills.

The object of the present invention is to improve the construction of joints for splicing the sills of wooden frame cars and analogous timbers, and to provide a simple, efficient and comparatively inexpensive splice clamp of strong and durable construction, adapted to be easily and quickly applied to a joint, and capable of obviating the necessity of employing the ordinary scarf board 20 and the bolts thereof.

With these and other objects in view, the invention consists in the construction and novel combination of parts hereinafter fully described, illustrated in the accompanying 25 drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing:—Figure 1 is a side elevation partly in section of a sill splice or joint, constructed in accordance with this invention. Fig. 2 is a plan view of the same. Fig. 3 is a reverse plan view. Fig. 4 is a transverse sectional view on the line 4—4 of Fig. 1. Fig. 5 is a horizontal sectional view on the line 5—5 of Fig. 1. Fig. 6 is a detail 40 perspective view of the bottom plate.

Like numerals of reference designate corresponding parts in all the figures of the drawing.

In the accompanying drawing in which is 45 illustrated the preferred embodiment of the invention, 1 and 2 designate splice ends of sills 3 and 4 designed for use in the construction of wooden frame cars, but the splice or joint may be advantageously employed 50 for connecting the ends of various other timbers or frame members. The splice ends 1 and 2 are formed by recessing the sills and the recessed ends are overlapped, as clearly shown in Fig. 1 of the drawing, 55 and are secured together by clamps located at the ends of splice joints, and each com-

prising a substantially U-shaped yoke 5, a bottom plate 6 and a U-bolt 7, which secures the bottom plate to the yoke and maintains the said parts in interlocked relation.

The yoke, which is constructed of malleable iron or other suitable metal, is composed of spaced parallel sides and a connecting top portion, and the sides are provided with depending corner lugs 8, which engage recesses 9 of the bottom plate 6. The bottom plate consists of a substantially oblong body portion and lateral extensions 10, projecting from opposite sides of the body portion centrally thereof and forming angles in the corners of which are arranged the recesses 9. The depending lugs 8 engage the recesses, which enable the bottom plate to be drawn up tightly against the sills, and at the same time the interlocking connection 75 formed by the lugs and the recesses prevents the spreading of the sides of the yoke.

The yoke is provided exteriorly of the top and sides with a central thickened or enlarged portion 11, and it has top and side 80 grooves 12 and 13, formed in the enlarged portion 11 and receiving the top connecting portion and the sides of the U-shaped bolt 7. The top groove, which is horizontal, extends entirely across the top of the yoke, and the side grooves are arranged vertically and extend from the terminals of the top groove to the lower edges of the sides of the yoke.

The approximately U-shaped bolt 7 is composed of straight sides and a straight connecting top portion, and the lower portions 14 of the sides are threaded for the reception of nuts 15, which engage the lower faces of the lateral extension 10 of the bottom plate. The top yoke is provided with terminal extensions 16 projecting beyond the side portions of the yokes and provided with centrally arranged perforations 16^a receiving vertical end bolts 17, piercing the sills at the overlapped splice ends and also beyond the same, as clearly illustrated in Fig. 1 of the drawing. The vertical end bolts are located beyond the transverse plane of the sides of the yoke. The lower terminals of the vertical end bolts extend through the 105 perforations 18 in the ends of the body portion of the bottom plate and are provided with nuts 19, engaging the lower face of the said plate. In order to prevent the vertical bolts 17 from turning when the nuts 19 thereof are screwed home, the yokes are provided at the top with projecting vertical

lugs or flanges 21, extending from the upper faces of the top portions of the yokes and located at the inner sides of the perforations 16^a and fitting against the adjacent edges of 5 the heads of the bolts 17. The lugs or flanges 21, which are formed integral with the yokes, are preferably of a width and length corresponding to the size of the heads of the bolts, and their upper edges are arranged 10 in flush relation with the upper faces of the bolt heads.

The clamps are arranged in overlapping relation with the terminals of the splice ends, which are also preferably connected 15 by a pair of vertical centrally arranged bolts 20, piercing the splice ends and arranged in spaced relation with the center of the joint and in line with the median vertical plane 20 of the sills. Any number of bolts 20 may, of course, be employed, but in the joints of the sills of wooden frame cars, two bolts are preferably employed.

What is claimed is:-

1. A clamp of the class described including 25 a yoke composed of spaced sides and a connecting top portion and having depending corner lugs arranged in pairs at the lower ends of the said sides, said yoke being also provided with connected grooves extending 30 across the top and down the sides of the yoke, a bottom plate having lateral extensions provided at opposite sides with

recesses receiving the said lugs, which interlock the yoke and the plate, and a U-bolt straddling the yoke and fitted in the said 35 grooves and piercing the lateral extensions of the bottom plate and provided with means for engaging the same.

2. The combination with two members having reduced overlapped portions to form 40 a splice joint, of clamps arranged at the ends of the joint and each including a substantially U-shaped yoke straddling the members at one of the terminals thereof and provided at its sides with spaced depending 45 projecting lugs, said yoke being also provided at the top with longitudinal extensions projecting inwardly and outwardly at the adjacent end of the joint, a bottom plate connecting the lower ends of the sides of 50 the yoke and engaged by the lugs thereof, a U-bolt straddling the yoke and piercing the lateral extensions of the bottom plate and provided with means for engaging the same, and spaced bolts extending through 55 the bottom plate and the extensions of the top yoke and piercing the overlapped portions of the members at the joint and one of the members thereof beyond the joint.

February the 7th, 1913.

JOHN YANCY SATTERWHITE.
